Primary Examiner — Eric Goodman*Assistant Examiner* — Christian P McLean(74) *Attorney, Agent, or Firm* — Finnegan, Henderson, Farabow, Garrett & Dunner LLP(57) **CLAIM**

The ornamental design for a display screen with animated graphical user interface, as shown and described.

DESCRIPTION

FIG. 1 is a front view of the first image in a sequence of a display screen with animated graphical user interface, showing our new design;

FIG. 2 is the second image in the sequence;

FIG. 3 is the third image in the sequence;

FIG. 4 is the fourth image in the sequence;

FIG. 5 is the fifth image in the sequence; and,

FIG. 6 is the sixth image in the sequence.

The appearance of the image transitions sequentially between the images shown within FIGS. 1-6. The process or period in which one image transitions to another forms no part of the claimed design. The broken line showing of the user and the display screen in all views is for environmental purposes only and forms no part of the claimed design.
